UNITED STATES PATENT OFFICE

THEA FINSTAD, OF MINNEAPOLIS, MINNESOTA

MOP

Application filed August 16, 1928. Serial No. 299,992.

My invention provides an improved mop adapted for general use but of particular design and especially adapted for use in connection with the mop pail with the funnel-like wringing device disclosed and claimed in a companion application, filed by me of even date herewith and entitled "Mop pail with wring attachment", #1,722,130 pat'd July 23, 1929.

10 This improved mop is of such design that the mop swab or rag, especially those of the cord type, may be readily replaced from time to time while maintaining the mop handle and head for continued use.

15 Generally stated, the invention consists of the novel construction and arrangement of parts hereinafter described and defined in the claim.

Referring to the drawings, which illustrate 20 the improved mop structure:

Fig. 1 is a side elevation of the complete mop with a portion of the handle broken away;

Fig. 2 is a view corresponding to Fig. 1, 25 but showing the parts on a larger scale and with some of the parts in section;

Fig. 3 is a plan view of the mop head;

Fig. 4 is a section on the line 3—3 of Fig. 3; and

30 Fig. 5 is a plan view of the mop anchoring device showing the same as it appears after having been stamped out, and before its anchoring prongs or grapples have been bent.

The mop handle or stick 6 is of an ordinary 35 wooden structure. The mop head, which is a cast metal structure, comprises a cylindrical socket 7 having at its lower end an outstanding annular flange 8. The interior of the socket 7 is formed with sharp-edged longitudinal ribs 9 that will cut into the bar 6 and securely hold the same within the socket 7. The flange 8, at diametrically opposite points, 40 is provided with anchor-receiving perforations 10. The above described parts constitute the permanent part of the complete mop.

The numeral 11 indicates a flat sheet metal anchor, the body of which is of disc-like form and of approximately the diameter of the flange 8 of the mop head. This disc-like body 50 11 has long outstanding bars or arms 12 and

the central portion of said disc 11 is slit to form anchoring barbs or portions 13. When the disc-like body 11 is placed against the flat bottom of the flange 8 and the prongs 13 are turned upward and passed through the perforations 10, said prongs can then be bent over the outer portion of the flange 8, as shown in Fig. 2, and thereby securely fasten the anchor 11 to the mop head.

The mop swab, which, as shown and preferably is of the cord type, is indicated by the numeral 14. When the group of cords 14 is divided into four parts and placed over the prongs 12 and the said prongs 12 are then bent inward and upward, against the disc-like body 11, as shown in Fig. 2, the cord-like mop swab will then be very securely attached to the mop head. When the mop swab is worn out, a new mop swab may be readily substituted. Sometimes this can be done by unbending and then rebending the prongs 12 without removing the anchor 11 from the mop head. Also the mop swab can be assembled and secured to the disc-like body 11 and sold as an entirety, ready for application 75 to the mop head simply by the proper insertion and bending of the anchoring prongs 13.

The mop described is a desirable and highly efficient mop for general use, but its head 80 being round and of small diameter, especially adapts the mop for use in connection with the wringing device of the mop pail disclosed and claimed in the patent above identified.

85 What I claim is:

The combination with a mop stick, of a mop head having a cylindrical socket provided at one end with an outstanding flange forming an extended substantially flat surface, said flange having diametrically opposite passages, a circular plate having diametrically opposite projections extended upward through said passages and peripherally disposed extending arms bent downward 90 and inward, and a mop swab held against said plate by said arms.

95 In testimony whereof I affix my signature.

THEA FINSTAD. 100
